RETRACTILE FOUNTAIN PEN

Orvel M. Johnson, Little Rock, Ark.

Application November 18, 1944, Serial No. 564,065

1 Claim. (CL. 120—49)

1

This invention relates to fountain pens and it consists in the constructions, arrangements and combinations herein described and claimed.

More particularly, it is an object of the invention to provide a fountain pen wherein the pen proper is normally housed in a casing, but projectable to expose the pen point for writing purposes, the pen proper including a catch means for holding the latter in exposed position, as well as including means for retracting the pen upon release of the catch.

It is also an object of the invention to provide a closure for the open end of the housing adapted to be moved to open position upon projection of the pen proper without liability of contact with the pen point.

Additional objects, advantages and features of invention will be apparent from the following description and accompanying drawing wherein

Figure 1 is a longitudinal sectional view of the pen, in closed position.

Figure 2 is an elevational view illustrating the pen in operative position.

Figure 3 is a cross section on the line 3—3 of Figure 1.

Figure 4 is a side elevation of the closure cap.

Fig. 5 is a plan view thereof.

Figure 6 is a side elevation of the base for mounting of the pen.

Figure 7 is a plan view of the pen removed from the housing.

Figure 8 is an end elevation of the pen housing with the closure cap removed, taken on the line 8—8 of Figure 1.

There is illustrated a housing 10 substantially cylindrical for the major portion of its length, the rear end being open and exteriorly threaded as at 11. A cylindrical cap 12 is employed interiorly threaded and complementary to the threads 11 of the barrel. The cap 12 is formed with an end opening 13 defined by an inwardly turned flange 14. The forward end of the housing 10 at the upper side is downwardly curved as at 15, a slight distance, the opening 16 being defined by forming the walls of the housing at a rearward inclination, as indicated at 17. The underside of the housing 10 at the opening 16 is formed with a flat portion 18, extending longitudinally of the housing a short distance, and upon each side of said portion, ears 19 are formed, as may be clearly seen in Figure 8. The ears are of elongated form, merging rearwardly into the wall of the housing 10. A closure cap 20 is mounted swingably between the ears 19 upon a pintle 21, the over-all dimensions thereof being such as

2

to fit flush with the opening 16; and upon the inner face of the cap a raised part 22 is formed of dimensions so as to engage within the opening 16. In order that the cap 20 may be held in releasable closed position, a leaf spring 23 is fixed to the cap and extended rearwardly a distance where it terminates in a recurved nib 24 which has bearing contact with the housing 10. As here shown, the spring 23 has a portion 23' embedded in the body of the cap. The spring is outwardly bowed as may be seen in Figure 1, exerting pressure upon the cap to maintain the latter in yieldable closed position. The spring also functions as a pocket clip, as will be appreciated.

Within the housing 10 a pen 25 is reciprocably mounted, consisting of a cylindrical pen base 26 upon the forward end of which there is mounted a pen 27. Upon the lower side of the base 26 a longitudinally extended tongue 28 is formed, complementary to a similarly extended groove 29 formed in the lower portion of the housing 10. The tongue and groove prevent rotation of the pen and insure a straight forward movement when the pen is to be projected. As may be seen in Figure 6, the tongue 28 extends beyond the forward end of the base 26 a distance so as to contact the raised part 22 in advance of the pen point 27.

The base 26 is formed with an exteriorly threaded part 30 and reduced terminal end 31, receiving thereon a collapsible ink sack 32. A barrel 33 is employed, having a closed rear end 34 and an interiorly threaded forward end 35 adapted to engage the threaded portion 30 of the base, the barrel being of a length to readily accommodate the sack 32 therewithin. The barrel 33 is formed with an elongated opening 36 and within the barrel there is secured a flat spring 37 which is disposed before the opening so that it may be readily flexed for the purpose of compressing the ink sack, as will be required in filling the pen.

A collar 38 is fixed upon the barrel 33 by means of a rivet 39 which also secures catch device 40. The collar 38 is so located upon the barrel that when the pen 25 is in retracted position the collar will abut the flange 14 of the housing.

A helical spring 41 is mounted upon the barrel 33 one end having bearing engagement with the collar 38 while the other end engages the terminal rear end of the housing 10. The spring urges the pen to its retracted position as may be seen in Figure 1.

The catch device 40 is a flat spring element, the rear end of which is formed with a notch 42 adapted to engage beneath the flange 14 when the pen is moved to operative position. In order to permit the necessary flexing movement of the spring, a recess or opening 42 is formed in the barrel 33 which will permit the catch to spring downwardly thereinto.

When it is desired to fill the pen, the cap 12 is removed and the pen may then be drawn rearwardly from the housing. The point 27 of the pen is deposited in an ink well or the like, and the sack 32 compressed by exerting pressure on the spring 37. Upon release of the spring, the sack will expand and ink will be drawn into the sack. The pen is now replaced in the housing, care being taken to see that the tongue 28 engages within the groove 29. The cap 12 is then engaged upon the housing. When it is desired to use the pen, inward pressure is exerted upon the end 34 of the pen, causing the latter to move longitudinally of the barrel, presenting the forward end of the tongue 28 against the raised part 22 of the closure cap. It will be noted that the tongue 28 engages the part 22 in advance of the pen point 27, so that damage to the latter is avoided. The closure 20 will be swung to open position with the pen point exposed. In this position the catch 40 will have become engaged with the flange 14 and the pen 30

will thus be held in operative position for writing. When it is desired to retract the pen, the catch 40 is depressed to release the flange, when the spring 41 functions to retract the pen into the housing, and at the same time, the spring 23 urges closure 20 to closed position.

While I have shown and described the invention specifically, this is by way of illustration only, and I consider as my own all such modifications in construction as fairly fall within the scope of the appended claim.

I claim:

A fountain pen comprising a housing having an open end, a pair of ears on the housing at one side of the open end, a closure cap hingedly mounted between the ears, a pen within the housing having an end projected through the open end of the housing, spring means within the housing operatively engaged between the pen and the housing, for holding the pen within the housing, said closure cap having a raised interior face, a tongue on said pen for engaging the raised face of the closure cap in advance of the point of said pen upon outward sliding movement of said pen, and a leaf spring having one end mounted in said closure cap for holding the closure cap releasable over the open end, the other end of the spring being recurved and normally contacting the housing.

ORVEL M. JOHNSON.
